HYDRAULIC SCRAPER

George E. Dean, Grand Rapids, Mich., assignor
to Charles G. Willett, Grand Rapids, Mich.

Application April 27, 1931. Serial No. 533,031

6 Claims. (Cl. 37—155)

This invention relates generally to road scraping mechanism and is more particularly concerned with means for operating the scraper blade to and from its operating position.

5 As set forth in my application for Road grader, Serial No. 506,152, filed January 2nd, 1931, hydraulic means may be utilized to both lower and raise the scraper blade but this has some objectionable features, as, for instance, the expense 60 of manufacturing a double acting cylinder and piston and hence, in the instant application, I replace the more or less complicated double action cylinder mechanism with a single acting unit combined with a novel spring return means. It 65 is also to be noted that I provide lever means for expediently installing the spring which connects to the scraper blade to lift the scraper blade from its operative position, this spring necessarily being of very stout construction.

10 Another feature of my invention resides in my method of supporting the cross channel upon the frame members of the truck. These side members have depending brackets which support parallel bars, as set forth in my patent application filed September 23rd, 1929, Serial No. 394, 70 408, and also have curved outwardly extending bars which lie in the same horizontal plane as the parallel bars. Strap members are rigid with the channel which carries the scraper blade 75 mechanism and these straps extend over the curved bars, thus supporting the scraping mechanism. Thus the cross channel member is supported by two separate and distinct means, the 80 one being permanently attached thereto and the other being adjustably attached to the parallel bars as set forth in my preceding patent application. This double support makes for ease of 85 adjusting the cross channel member, especially when the scraping mechanism is used on trucks having very low frames.

Another feature lies in my flexible dust arrester which surrounds the connecting rod and thus prevents dust from entering into the cylinder at its lower end.

45 Also, I utilize the lever which supports or holds the upper end of the tension springs for returning the scraper blade to its inoperative position, as a guarding means for the cylinder, this lever being of U-shaped construction and surrounding the top of the cylinder.

Briefly described, my invention consists of a cross channel member from which the scraper blade depends, this cross channel member having a vertically positioned cylinder at either end thereof. These cylinders are positioned on the

top side of the cross channel member and pistons which operate in these cylinders are connected to the scraper blade whereby they may be pushed to operative position or retracted therefrom. The downward movement of the piston pushes the blade to operative position and a spring, previously referred to, withdraws the blade upwardly and consequently returns the piston to the upper part of the cylinder. Hydraulic pressure means above the piston causes 65 its actuation downwardly to operate the scraper blade to its operative position.

In the drawings and specification, which illustrate a preferred embodiment of my invention as required by the patent statutes, a double arrangement of parts is shown, there being two scraper blades, two moldboards, two sets of double torsion springs and two rock shafts actuated by two hydraulically operated cylinder-piston arrangements, but it is to be understood 70 that my invention is equally applicable to a single unit of this character. Or, if desired, three or more units may be utilized.

The above and more specific objects herein- 75 after appearing are attained by, and the invention finds preferable embodiment in the structure hereinafter particularly described in the body of this specification and illustrated by the accompanying drawings, in which,

Fig. 1 is a plan view of the chassis on a truck 80 equipped with an oscillatable cross beam, this cross beam carrying the hydraulic means whereby the scraper blades may be adjusted.

Fig. 2 is a view in cross section, this view being taken along the line 2—2 of Fig. 1.

Fig. 3 is a side view of the truck, this view being broken away in part in order to expedite the showing.

Fig. 4 is a view taken in the direction indicated by the arrow A, of Fig. 3, this view illustrating the control valve and gauges for the actuation of the scraper blade mechanism.

Fig. 5 is a side view of one of the hydraulic cylinders with the lever mechanism for supporting the tension springs for the scraper blade.

Fig. 6 is a cross sectional view taken through one of the hydraulic cylinders and its pistons, this figure clearly showing the flexible dust arrester.

Similar numerals refer to similar parts 95 throughout the several views.

Referring to the drawings, numeral 10 indicates the side members of the truck or vehicle upon which the scraping mechanism is mounted, and brackets or hangers 11 are bolted to and 100 110

depend from these side members. See Figs. 1, 2 and 3. The hangers 11 support spaced parallel bars 12, these bars slidably receiving hook members 13 therebetween, which in turn carry 5 the main cross channel supporting beam 15, and these hangers also support curved bars 14, these bars being bent concentrically about the axis of rotation of the cross channel member 15. Strap members 16 are rigidly attached to the upper 10 side of the channel member 15 and extend over the curved bars, as clearly shown in Fig. 2, and hence permit the cross channel member 15, which carries the scraping blade mechanism, to oscillate with respect to the truck, as illustrated 15 by the dotted line showing of Fig. 1.

From the above description it will be seen that by loosening the hook members 13 the cross channel member 15 and its dependent structure, may be adjusted to assume a position crosswise 20 of the truck as desired. Then, by tightening the hook members 13 the cross channel is rigidly held in the chosen position. The strap members 16 ride upon the curved bars 14 during the adjusting operation.

25 The cross channel 15 carries brackets 20 which receive the rock shafts 21, these rock shafts being in alinement with each other and also similar in construction except that one is right-hand and the other is left-hand. Double torsion springs 22 are rigidly connected to the rock shafts in the usual manner and these springs in turn support moldboards 23 and these moldboards in turn support the scraper blades 24. See Figs. 2 and 3.

35 Cylinders 30 are mounted upon the cross channel 15 at either end thereof and as these cylinders are substantially duplicates of each other only one will be described in detail. The cylinder 30 is threadedly engaged in a base plate 31, see Fig. 6, and a hooked bolt 31 holds one edge of the base plate 31 to the channel member 15. Bolts 32, see Fig. 5, extend through the feet of the fulcrum members 35 and then through the base plate 31 and next through the 40 web of the cross channel 15 thereby holding these parts in assembled relationship.

A U-shaped lever 36 is pivoted as at 37 upon the upper end of the fulcrum member 35 and the curved end of this U-shaped member has a 45 hole therethrough whereby fastening means may be inserted therein and also through a vertical bracket member 38, rigidly connected to the channel member 15 as at 39, to thereby maintain the lever 36 in a substantially horizontal position, whereby the spring 40 will be tensioned for the purposes to be set forth. Also, in passing, the U-shaped lever 36 surrounds the cylinder 30 and protects or guards it from being struck inadvertently.

50 The moldboards 23 have brackets 41 thereon, see Fig. 2, and a pin 42 extends through these brackets and also through the lower ends of the springs 40 thereby attaching the lower ends of these springs to the scraper blade.

55 Springs 40 must be installed under considerable tension in order that they may have power enough to pull the scraper blade and the moldboard to an inoperative position and also to return the piston 60 to its upper position, and by means of the lever mechanism just set forth this installation is easily had. Such is accomplished by turning the U-shaped lever 36 to the position shown in Fig. 5, whereby its ends are lowered, thus facilitating the attachment of the 60 springs 40 thereto. Next the other closed end

of the lever 36 is pulled downwardly and attached to the upper end of the bracket member 38, the several parts assuming the position shown in Fig. 3. During this installation it is necessary to have the moldboard and scraper blade in their upper or inoperative position.

80 Each rock shaft 21 has a crank member 45 extending therefrom, see Figs. 2 and 3, and a connecting rod 46 is pivotally attached thereto and extends upwardly into the cylinder 30, being pivotally attached to the piston 60 by means of the wrist pin 61. The piston 60 is equipped with cup leathers 62 as clearly shown in Fig. 6. A flexible dust arrester 63 is attached around the upper end of the connecting rod 46 and extends loosely downwardly therearound, the lower end of this flexible fabric being held in place by the snap ring 64 which fits into a groove in the base plate 31. The cylinder 30 has a cap 65 and an inlet pipe 66 leads therefrom, this inlet pipe furnishing the pressure fluid whereby the piston 60 is forced downwardly. A conduit 66 leads from each of the cylinders 30 and valves 67 are positioned at the ends of these passages 66. A cross fitting 68 has connections with the 100 other side of said valves.

85 Suitable pressure gauges 70, see Fig. 4, indicate the pressure which is actually being applied to either of the scraper blades. One of the two remaining ports of the cross fitting 68 has a 105 conduit 71 leading therefrom to the electrically operated pump 72, this pump being of any suitable type and being driven by the electric motor 73, usually motivated by the storage battery of the automobile, (not shown), and a check 110 valve 74, see Fig. 1, maintains the pressure in the cylinders. The remaining port of the cross fitting 68 leads back to the inlet pipe of the pump to a connection 76, having a release valve 77.

115 The operation of these hydraulic means is easily understood. The motor 73 operates the electric pump 72 thereby furnishing fluid pressure through the pipe 71 and the check valve 74. Thus, assuming the valves 67 to be open, this pressure fluid is carried to the upper side of the pistons 60 in the cylinders 30 and thus these pistons are forced downwardly thus turning the rock shafts about their respective axes and pushing the scraper blade downwardly to 120 their operative positions. Also, during this downward movement the several springs 40 are extended and tensioned and hence, when the pressure is afterwards released, as by opening the valve 77, the scraper blades return upwardly 125 to their inoperative positions due to the action of the springs 40.

130 From the above description it will be appreciated that I have invented a unit of this character which will not only operate efficiently but which may be manufactured very cheaply, due to the fact that there are very few parts necessary, and furthermore that these parts do not require close machine work thereon. Hence, I 135 desire to protect my invention as set forth in the following claims.

I claim:

140 1. In combination, a beam, a cylinder mounted thereon, a scraper blade pivotally mounted upon the beam, a piston operatively associated with said cylinder, means to operate the piston in one direction, connecting means between the piston and the blade whereby actuation of the piston by the aforesaid means causes the scraper blade to move in one direction, a fulcrum mem- 145

ber mounted upon the beam, a lever pivoted upon said fulcrum member, a spring connected at one end to the end of said lever and at the other end to the scraper blade and means for fastening the other end of said lever at a chosen point whereby the spring is placed under the desired tension.

2. A combination of elements as set forth in claim 1 but further characterized by the fact that the lever pivoted upon the furcrum member partly surrounds the cylinder thereby serving as a guard therefor.

3. In combination, a horizontal cross beam, a scraper blade pivotally mounted below and upon said cross beam, a vertical cylinder having a closed upper end mounted upon said cross beam, a piston mounted in said cylinder, means connecting the piston and the blade whereby movement of the piston causes corresponding movement of the blade, fulcrum members attached to the cross beam and extending upwardly on either side of the cylinder, a U-shaped guard member having pivotal connections near its ends to the upper ends of said fulcrum members, springs extending from the ends of said U-shaped guard member downwardly and being fastened to the scraper blade and means for holding the curved end of the U-shaped member against upward movement.

4. In combination, a beam, a cylinder mounted thereon, a scraper blade pivotally mounted upon the beam, a piston operatively associated with said cylinder, means to operate the piston in one direction, connecting means between the piston and the blade whereby actuation of the piston by the aforesaid means causes the scraper

blade to move in one direction, a spring connected at one end to the scraper blade and means fastened to the other end of the spring for tensioning and fastening the same.

5. In a device of the character described, a cross beam having an opening therethrough, a scraper blade, means for pivotally mounting the scraper blade upon the cross beam, hydraulic means including a vertical cylinder mounted over said opening, a piston and a connecting rod for turning the blade downwardly about its pivot to working or operative position, said connecting rod extending through the said opening and spring means for returning the blade to its upper inoperative position, said spring means also returning the hydraulic means to its initial position.

6. In a device of the character described, a cross beam, a scraper blade, a rock shaft for pivotally mounting the scraper blade upon the cross beam, a base plate having an opening therethrough, fastening means for attaching the base plate rigidly to the cross beam, a cylinder rigidly mounted on said base plate around said opening and extending vertically upward, a piston located in said cylinder, a connecting rod pivotally connected to and extending downwardly from said piston, means rigidly extending from said rock shaft, said lower end of the connecting rod being pivoted onto the last mentioned means whereby movement of the piston causes movement of the rock shaft and spring means for returning the blade to its upper inoperative position.
